METHOD AND DEVICE FOR GRINDING
COOPERATING FACES OF FRICTION MEM-
BERSJean Cotal, Paris, France; vested in the Alien
Property CustodianApplication May 31, 1940, Serial No. 338,266
In France June 24, 1939

10 Claims. (Cl. 29—89.5)

The present invention relates to a method and apparatus for grinding and hardening elements of magnetic couplings.

In the case of clutches, brakes, speed-changing boxes, and various controlling devices, magnetic discs are coming into increased use, these being coupled by means of electric current.

It has been found preferable, in practice that the surfaces adapted to make contact for the necessary transmission of power, should be subjected to a preliminary hardening.

The present invention relates to a mechanism adapted for the automatic grinding, in order to obtain such hardening, of the magnetic discs and their cooperating electro-magnets used for clutches, brakes, speed-changing boxes, etc., and of all similar devices.

The said mechanism is chiefly characterized by the fact that it is so constructed that the power required for the grinding is produced by varying the kinetic energy of one or more rotary parts.

Further characteristics will be set forth in the following description.

In the accompanying drawings, which are given solely by way of example:

Fig. 1 is a longitudinal section of a mechanism in conformity to the invention which serves for the simultaneous grinding of four groups of coupling devices comprising magnetic discs and electro-magnets.

Fig. 2 shows a half cross-section on the line 2—2 of Fig. 1, and a half cross-section on the line 2'—2', of the same mechanism.

Fig. 3 is a longitudinal section of another mechanism which serves for the grinding of boxes having several speeds, provided with electro-magnetic couplings.

In the embodiment shown in Figs. 1 and 2, the mechanism comprises a rotary electro-magnet 1 mounted on a shaft 2 which is keyed or otherwise secured to the shaft of an electric motor 3. The said electro-magnet, when excited, can attract an armature 4 which is adjacent the same and is loose on an extended part of the shaft 2. The said armature 4 is secured, as to rotation, to a pinion 6 engaging pinions 7 which are disposed around this pinion and are secured to the magnetic discs 8 to be ground with the electro-magnets 9 with which they are to cooperate when in use. The pinions 7 and the discs 8 are loosely mounted on cylindrical axial extensions 10 of the electro-magnets 9. These latter are mounted on fixed journals 11 secured to the casing 12 of the mechanism, and each electro-magnet 9 is prevented from rotating on a journal 11 by the en-

gagement of a toothed ring 13 with a fixed central pinion 14 secured to the casing of the grinding mechanism. The said casing consists, for example, of two parts 12 and 12^a, whose joint is in a vertical plane.

The apparatus operates in oil contained in the said casing. This latter is provided with a pump 15 which withdraws the oil through a conduit 16 and discharges it, for instance, into an axial channel 17 formed in the driving shaft 2 which is pierced with radial holes 17^a for the lubrication of the hub of the device and a certain part of the oil circulates into a chamber 18 provided at the end of the shaft 2. This chamber is connected, for instance by conduits 19, to the journals 11, which are hollow and are pierced, as well as the hubs of the electro-magnets, with oil holes 20 adjacent the hubs of the discs 8.

The direct current required for energizing the various electro-magnets is supplied by a source of current 21. The current is distributed by a circular switch 22, whose rotating arm 23 is connected to one terminal of the source of current 21 and is driven by the shaft 2 by means of pulleys 24 and 25 and a cable 26. The switch arm will send the current alternately into the electro-magnet 1 connected to the source of current by a conductor 27, and to the contact pieces 28 of the circular switch 22, by a conductor 29, and into the electro-magnets 9 which are connected to the source of current by conductors 30 and to a second set of contact pieces 31 of the circular switch by conductors 32.

The operation is as follows. When the electric motor is set running, the arm 23 which is driven by the motor shaft, sends the current into the electro-magnet 1, and this latter, by means of the armature 4, drives the pinions 6 and 7 and the armatures 8.

Immediately afterwards, the arm 23 breaks the circuit of the electro-magnet 1 and sends current into the fixed electro-magnets 9 which brake and stop the armatures 8 and 4, in spite of their kinetic energy. Then continuing its movement, the arm 23 breaks the circuit of the electro-magnets 9, and the current is sent into the electro-magnet 1, which is constantly in rotation, and this latter again drives the armature 4, and the armatures 8, and the cycle of the driving and stopping of these armatures is repeated.

During the braking which is required in order to absorb the kinetic energy until the stopping occurs, friction will take place between the faces of the armatures 8 and of the electro-magnets

9, and by reason of this braking action, the surfaces will be ground and hardened.

After a certain number of operations, the discs 8 and the electro-magnets 9 are removed for use in clutches, brakes or speed-changing mechanisms without danger of seizing, in the case of the couplings for which they are employed.

It is evident that the said apparatus may comprise if necessary, for the grinding, a greater number of electro-magnets and armatures such as 8 and 9, and that a greater or less speed of grinding for the whole set of these pieces can be readily obtained by varying the speed of the parts subject to friction, and by varying the weight of certain pieces having a variable movement. For instance, it is possible to increase or diminish the ratio of the gearing 6 and 7, or to increase or diminish the weight of the armature 4, and thus to obtain more or less kinetic energy which is to be absorbed by the grinding work.

The apparatus represented in Fig. 3 comprises, as in Figs. 1 and 2, a revolving electro-magnet 1 secured to the driving shaft 2, which latter, by way of example, is actuated by belt and pulley 33. An armature 4, which may be driven by the electro-magnet 1, is secured to the shaft 35, which extends into the grinding box.

The box shown in the figure is of the known type having two speeds which are obtained by hypocycloidal gearing which comprises the following magnetic parts: an electro-magnet 34 mounted on the driving shaft 35 and secured to a main gear-wheel 36 of a planetary set, an electro-magnet 37 secured to the casing 38 of the box, and an armature 39 secured to the other main gear wheel 40 of the planetary set, the planetary pinion carrier 41 being mounted on the driven shaft 42.

The box is located in the casing 38 which contains oil and is mounted on the casing 12^a of the grinding mechanism.

The electro-magnet 1 is directly connected to the terminals of the source of current 21 by conductors 27 and 43. The electro-magnets 34 and 37 are connected directly to the source of current 21 and by conductors 44 and 45, to the alternate contact pieces 46 and 47 of the circular switch 22 whose arm 23 is actuated by the motor and is connected to the other terminal of the source of current 21.

The operation is as follows. During the whole time of the grinding, the electro-magnet 1 is excited and it constantly drives the armature 4 and the electro-magnet 34.

The variation of the kinetic energy, which is necessary for the grinding work, is produced in this case by varying the speed of the armature 39, which is alternately driven at the speed of the electro-magnets 1 and 34 and stopped by the electro-magnet 37, as the switch 22 will alternately excite the electro-magnets 34 and 37.

The grinding takes place by the friction of the surfaces, as in the device shown in Fig. 1, but in this case, the armature 39 has two operating faces. The face adjacent the electro-magnet 34 is ground during the engagement of this armature, which proceeds from a zero speed to the speed of the electro-magnet 34. The face adjacent the electro-magnet 37 is ground during the braking of this armature, which proceeds from the speed of the driving shaft to a zero speed.

Obviously, the invention is not limited to the

embodiments herein described and represented, which are given solely by way of example.

In the appended claims, the word "speed" is to be understood for any absolute value, either positive, or negative or null.

Having now described my invention, what I claim as new and desire to secure by Letters Patent is:

1. A method for grinding cooperating faces of members of devices operating by friction and particularly of electromagnets and armatures for the same which consists in, repeatedly effecting at regular intervals the cycle of operations comprising separating said members from each other, rotating one of said members and maintaining the other stationary, allowing any one of said members to rotate freely, and urging said members towards each other so as to bring said cooperating faces into close contact whereby said cooperating faces are ground due to the friction taking place between said faces.

2. A method for grinding cooperating faces of members of devices operating by friction and particularly of electromagnets and armatures for the same which consists in repeatedly effecting at regular intervals the cycle of operations comprising separating said members from each other, maintaining one of said members stationary and rotating the other member, allowing said other member to rotate freely, and urging said members towards each other so as to bring said cooperating faces into close contact whereby said cooperating faces are ground due to the friction taking place between said faces until said members are both stationary.

3. A method for grinding cooperating faces of members of devices operating by friction and particularly of electromagnets and armatures for the same which consists in, repeatedly effecting at regular intervals the cycle of operations comprising separating said members from each other, maintaining one of said members stationary and rotating the other member, allowing said first member to rotate freely, and urging said members towards each other so as to bring said cooperating faces into close contact whereby said cooperating faces are ground due to the friction taking place between said faces until said members rotate at the same speed.

4. A device for grinding cooperating faces of members of devices operating by friction and particularly of electromagnets and armatures for the same comprising, driving means, means adapted to support said members independently of said drive means with their cooperating faces coaxially disposed, said driving means being adapted to rotate one of said members and retaining means adapted to maintain the other of said members stationary, one of said driving and retaining means being releasable, releasable attracting means adapted to press said cooperating faces of said members against each other, and controlling means adapted to make operative successively and alternately at regular intervals said two releasable means.

5. A device for grinding cooperating faces of members of devices operating by friction and particularly of electromagnets and armatures for the same comprising, means adapted to support said members with their cooperating faces coaxially disposed, means adapted to maintain fixedly one of said members, releasable driving means adapted to rotate positively the other member, releasable attracting means adapted to press said cooperating faces of said members

against each other, and controlling means adapted to make operative successively and alternately at regular intervals said driving means and said attracting means.

6. A device for grinding cooperating faces of members of devices operating by friction and particularly of electromagnets and armatures for the same comprising, means adapted to support said members with their cooperating faces coaxially disposed, means adapted to maintain fixedly one of said members, a driving shaft, electromagnetic clutch means having its driving part operatively connected with said driving shaft and its driven part operatively connected with the other of said members, an electromagnet on one of said members adapted to attract the other member so as to press said cooperating faces of said members against each other, and electric current supplying means including switch means adapted to circulate current successively and alternately at regular intervals through said clutch means and through said electromagnet.

7. A device for grinding cooperating faces of members of devices operating by friction and particularly of electromagnets and armatures for the same comprising, a central rotatable shaft, a plurality of supporting means distributed about said shaft and each adapted to support at least two members to be ground with their cooperating faces coaxially disposed, means adapted to maintain fixedly one of said members on each supporting means, transmission means between said central shaft and the other of said members on each supporting means and adapted to transmit rotation from said shaft to said other member on each supporting means, releasable driving means adapted to rotate positively said central shaft, releasable attracting means adapted to press said cooperating faces of said members against each other on each supporting means, and controlling means adapted to make operative successively and alternately at regular in-

tervals said driving means and said attracting means.

8. A device for grinding cooperating faces of members of devices operating by friction and particularly of electromagnets and armatures for the same comprising, means adapted to support said members with their cooperating faces coaxially disposed, driving means adapted to rotate one of said members, releasable retaining means adapted to maintain the other of said members stationary, releasable attracting means adapted to press said cooperating faces of said members against each other, and controlling means adapted to make operative successively and alternately at regular intervals said two releasable means.

9. A device for grinding cooperating faces of members of devices operating by friction and particularly of electromagnets and armatures for the same comprising, supporting means adapted to support adjacent each other three members, two opposite faces to be ground of the central member being adapted to cooperate respectively with one adjacent face to be ground of each of the outer members, releasable attracting means on each outer member adapted to press the cooperating faces of said outer member and of said central member against each other, driving means adapted to rotate one of said outer members, retaining means adapted to maintain stationary the other outer member, and controlling means adapted to make operative successively and alternately at regular intervals the releasable attracting means on said outer members.

10. A device according to claim 9 in which said attracting means consist of electromagnets and said central member of an armature, and said controlling means consist of electric current supplying means including switch means and adapted to successively and alternately at regular intervals energize said electromagnets.

JEAN COTAL.
